JOHN G. ZOLLEIS, OF PHILADELPHIA, PENNSYLVANIA, ASSIGNOR TO TEST-TITE COMPANY, A PARTNERSHIP CONSISTING OF PAUL PANHORST AND JOHN G. ZOLLEIS, OF PHILADELPHIA, PENNSYLVANIA.

BATHROOM FIXTURE.

Application filed August 17, 1926. Serial No. 129,729.

This invention is an improvement in bathroom fixtures, and relates more particularly to means enabling the projecting parts of taps, valves and the like to present an ornamental smooth finished and ornamental appearance.

Such fixtures, usually valves or taps, are of standard lengths, including a valve casing adapted to extend through an opening in the wall, an escutcheon, and a nut threaded onto the casing to engage the escutcheon and hold it in place. The escutcheons of porcelain or the like are of a frusto-conical form, abutting the wall at their large end, while the small end is engaged by the collar.

Such walls are not always of the same thickness, and with standard size casings it may happen that the casing is too short or too long for the wall opening. The casing must be threaded from its outer end to permit the use of a threaded collar, and if the wall is thicker than the purported dimensions, the collar cannot engage the threads. If on the other hand the wall thickness is less than the purported dimensions, the threads of the casing will be exposed presenting an unpleasing appearance.

It is desirable in bathroom fittings of all kinds that all parts be surface finished, as for instance nickel plated, smooth, and as free as possible from depressions of any character which are liable to catch foreign matter, and the bottoms of which are particularly susceptible to oxidation. Threading is particularly objectionable in that it mars the finish, makes plating impracticable, and provides a surface very difficult to clean and to keep clean.

One of the primary objects of the present invention is the provision of a fixture of the character in question, so arranged that the entire fixture will present on the bathroom side a smooth surface finished of an ornamental nature.

Another object is the provision of a fixture of the character in question presenting all of the appearances of the usual fixture and without material increase in the cost thereof.

With these and other objects in view the invention consists in the construction and

novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:

Fig. 1 is a perspective view of the improved fixture in place.

Fig. 2 is a horizontal section of the wall and the escutcheon with the fixture partly in section.

In the present embodiment of the invention, the improved fixture includes a valve casing 1 of the usual construction, which is adapted to extend through an opening 2 in the wall 3 of a bathroom. The fixture includes also a valve, not shown, operated by a stem 4, having the usual handle 5.

A packing means of usual construction is provided for the stem, including as a part thereof a housing sleeve 6 encircling the stem between the handle and the casing, and held in place by means of a nut 7 threaded onto the sleeve and abutting the end of the casing 1. The housing sleeve is relatively long as shown, extending from the nut 7 to near the handle 5, and the said sleeve is surface finished.

The surface finish may be in the form of plating, as for instance nickel, and the surface of the sleeve is smooth and free from depressions of every character. If desired a part thereof at the inner end may be roughened, or unfinished, for facilitating the grip of nippers when turning the sleeve into place. In the drawings this part is indicated at 8.

The escutcheon 9, which may be of any suitable material, as for instance porcelain, is substantially frusto-conical in shape, the small end encircling the housing sleeve, while the large end is adapted to engage the wall 3 of the bathroom. Preferably the escutcheon is of a size at the small end somewhat greater than the diameter of the sleeve, so that an annular space is provided between the escutcheon end and the sleeve.

In order to hold the escutcheon in place, a collar 10 is slidably mounted on the sleeve, the collar being adapted to abut the small end of the escutcheon, to hold it 5 against the wall, and the collar has a tubular extension 11 fitting within the escutcheon, and serving to fill the annular space before mentioned thus to properly center the escutcheon. A set screw 12 is threaded 10 through the collar, and is designed to engage the sleeve, to clamp the collar thereto in adjusted position.

The collar is surface finished in the same manner as the sleeve and the exposed part 15 of the valve stem, which when the valve is closed is so small as to be negligible. In practice the set screw 12 will be on the underside of the fixture, so that it is hidden.

In the construction described, the walls 20 with which it is used may vary greatly in thickness from the purported dimensions, and the fixture will still present on the bathroom side a pleasing surface, all parts of which are finished and ornamental. The 25 housing sleeve 6 is of sufficient length to extend well beyond the escutcheon even with a wall much thicker than usual. In practice the sleeve may extend beyond the casing two inches more or less, thus to provide for at 30 least an inch variance in wall thickness. When the valve is closed, the handle 5 is so close to the end of the sleeve that it appears to be the valve stem.

While the collar is shown as provided with 35 the tubular extension 11, it is obvious that the opening at the small end of the sleeve might be of a diameter such that no tubular extension would be necessary on the collar to center the valve. The improved fixture 40 enables the parts which project into the bathroom to present an entirely finished appearance, surface plated throughout, easily cleaned and kept clean, and not susceptible to oxidation.

45 What is claimed as new is:

1. A bathroom fixture, such as a valve, adapted to extend through an opening in a bathroom wall and capable of use with walls 50 of different thickness to present a wholly smooth, finished and ornamental surface on the bathroom side regardless of the wall thickness, comprising a casing, a valve stem, and a packing means for the stem, the packing means including a smooth surface finished housing sleeve encircling the stem and extending from the casing to near the end of the stem, a substantially frusto-conical escutcheon encircling at its small end the sleeve and adapted at its large end to abut 55 the wall, and a collar fitting the housing sleeve and abutting the end of the escutcheon to hold it in place, the collar having means to clamp the same to the sleeve in adjusted position.

65 2. A bathroom fixture, such as a valve,

adapted to extend through an opening in a bathroom wall and capable of use with walls of different thickness to present a wholly smooth, finished and ornamental surface on the bathroom side regardless of the wall 70 thickness, comprising a casing, a valve stem, and a packing means for the stem, the packing means including a smooth surface finished housing sleeve encircling the stem and extending from the casing to near the end of the stem, a substantially frusto-conical escutcheon encircling at its small end the sleeve and adapted at its large end to abut the wall, and a collar fitting the housing sleeve and abutting the end of the escutcheon 75 and provided with means to clamp the collar to the sleeve, said collar having a tubular extension fitting within the small end of the escutcheon to center the same.

3. Means enabling the projecting parts of 80 bathroom fixtures such as taps or valves to present a wholly finished surface, comprising a housing sleeve for the valve stem adapted to extend from the casing to near the handle of the stem, a substantially frusto-conical 85 escutcheon encircling the housing sleeve and adapted to abut the wall at its large end, and a holding collar for the escutcheon encircling and fitting the housing sleeve and having means 90 to fix the collar on the housing sleeve, the collar, housing sleeve and valve stem finished to provide a smooth surface from the 95 bathroom wall to the valve stem handle.

4. In combination, a valve casing adapted 100 to extend through an opening in a wall, a valve stem, and a packing means for the stem including a housing sleeve, an escutcheon encircling the housing sleeve and 105 adapted to engage the face of the wall, the housing sleeve and stem extended beyond the casing to provide for different thicknesses of wall, the housing sleeve smooth surface finished from near the casing end, and a collar freely slidable on the housing 110 sleeve to engage the escutcheon and hold it in place, and having means to clamp the collar on the housing sleeve.

5. Means enabling the projecting parts of 115 bathroom fixtures such as taps or valves to present a wholly finished surface, comprising a housing sleeve for the valve stem adapted to extend from the casing to the handle of the valve stem and to cover substantially all of the stem, a substantially frusto-conical 120 escutcheon encircling the housing sleeve at its small end and adapted to abut the wall at its large end, and a holding collar for the escutcheon slidable on the housing sleeve and having means to secure 125 it thereto.

6. Means enabling the projecting parts of 130 bathroom fixtures such as taps or valves to present a wholly finished appearance, comprising a housing sleeve for the valve stem

adapted to extend from the casing to the handle of the stem and to cover substantially all of the stem, a substantially frusto-conical escutcheon encircling the housing sleeve at its small end and adapted to abut the wall at its large end, and means to secure the escutcheon to the housing, said escutcheon adapted to cover and conceal the end of the casing and the adjacent end of the housing sleeve, and freely slideable on the housing when the securing means is released.

Signed at Philadelphia, in the county of Philadelphia and State of Pennsylvania, this thirteenth day of August A. D. 1926.

JOHN G. ZOLLEIS.
